CLAIM

The ornamental design for a clamping terminal of connector as shown and described.

DESCRIPTION

FIG. 1 is a perspective view of a clamping terminal of connector showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is another perspective view showing the clamping terminal of connector; and,

FIG. 9 is a perspective view showing two clamping terminals mounted on a connector.

(Continued)

The broken lines shown in the figures are for the purpose of illustrating portions of the clamping terminal of connector and form no part of the claimed design.
